(57) CLAIM

The ornamental design for a can, as shown and described.

DESCRIPTION

FIG. 1 is a perspective view of a can showing my new design;

FIG. 2 is a top view thereof;

FIG. 3 is a front view thereof, the right side, left side and back views being identical;

FIG. 4 is a bottom view thereof; and,

FIG. 5 is a cross sectional view thereof, taken along line 5—5 of FIG. 2.

The broken lines shown in the drawing disclosure are for illustrative purposes only and form no part of the claimed design.
